UNITED STATES PATENT OFFICE.

DAVID LANCASTER DWINNELL, OF MONTREAL, QUEBEC, CANADA, ASSIGNOR
OF ONE-HALF TO MILLER BRAS & TOMS, OF SAME PLACE.

HOT-WATER BOILER.

SPECIFICATION forming part of Letters Patent No. 413,432, dated December 23, 1890.

Application filed September 5, 1890. Serial No. 363,982. (No model.)

To all whom it may concern:

Be it known that I, DAVID LANCASTER DWINNELL, of the city of Montreal, in the district of Montreal and Province of Quebec, 5 Canada, have invented certain new and useful Improvements in Hot-Water Boilers; and I do hereby declare that the following is a full, clear, and exact description of the same.

This invention relates to that class of boilers 10 or heating-furnaces generally used in connection with a system of hot-water pipes and coils, or pipes and radiators, used for warming buildings, and has for its object simplicity and cheapness in construction, together with a more rapid heating of the water.

The improvement consists in the combination, with the fire-chamber and a water-jacket surrounding same and communicating with the supply and return pipes, of water- 20 sections in the form of hollow disks or chambers having central apertured hub portions through which the water enters, central dia- 25 phragms which spread the water outward or radially from the center of the sides and fire-flues, such hub portion being of greater depth than the outer edges or peripheries of the disk, so as to secure tapering sides, and the whole being held together by a stay passing centrally through the uppermost sections and 30 having one end secured within the lowermost section and the other end to the uppermost section. For full comprehension, however, of the invention reference must be had to the accompanying drawings, forming part of this 35 specification, in which like symbols indicate corresponding parts, and wherein—

Figure 1 is a part vertical elevation and section of my improved boiler or furnace; and Fig. 2, a complete vertical section of same, 40 taken centrally from front to back, Figs. 3 and 4 being horizontal sections respectively on lines $x x$ and $z z$, Fig. 1.

A is the base section of the furnace, and B the fire-chamber section having water-jacket B', which are of the usual construction. On 45 top of the water-jacket B the lowermost water-section C is fitted, so that openings c c in its bottom side will communicate with similar openings, as b, in the top of the water-jacket,

and upon this section C are built up any desired number of intermediate sections C' C' C', which are finally capped by a head section C², forming the top of the boiler. These several sections C, C', and C² are each in the form of hollow disks or chambers, the intermediate ones C' tapering on both sides from central hub portions D' D' to their peripheries, while the lowermost and head sections C C² have, respectively, only their upper and lower sides tapering from hub portions D D², 55 their respective bottom and top sides being flat and devoid of such hub portions.

Communicating opening d, d', and d² are respectively formed in the hub portions D, D', D', and D², and the intermediate sections C' are further provided with diaphragms E, carried centrally by web-supports e e, extending from the hub portions D' D' to them. These diaphragms E are of greater diameter than the openings d, d', and d² and extend about 60 half-way to the peripheries of the sections, so as to partially divide them into upper and lower halves, and thus compel the water entering through the lower openings to travel radially in the lower half from the center toward the peripheries and back in the upper half toward the upper central opening.

Flues F F' for the products of combustion are respectively formed in the lowermost section C and each of the intermediate ones C' C', 80 and the several sections are so placed with relation to each other that such flues will alternate in position, in order to secure zigzag passages for such products of combustion, a single flue F² being provided in the top section 85 C², which communicates with the usual pipe. The water-sections are inclosed by a shell G, and the whole held together by means of a stay H, having one end screwed into a frog H', (which bears on the under side of the hub 90 portion D of the lowermost section,) and extending centrally up through the several dia- 95 phragms E, pierced for it, and through the top of the head-section C² to receive a cap-nut H², the lowermost section C being secured to the fire-chamber section B by means of bolts b² passing through section C and tapped into section B. K is the opening where the re-

turn-pipes communicate with the water-jacket at its lowest point, and L L the flow-pipes leading out of the head-section C², all of which are arranged as usual and require 5 no special mention.

It will be apparent to those thoroughly acquainted with the nature of hot-water heating that spreading the volume of water into comparatively thin sheets of very large area over 10 highly-heated surfaces, as is the case with the sections shown, must quicken to a considerable extent the heating of the water, especially when the areas of the sheets of water are no more than that of the inlet and outlet, and 15 it will be further noticed that the tapering form of the sections provides a course of travel quite in keeping with the natural inclination of hot water to rise, and, furthermore, facilitates cleaning operations.

20 The operation of the boiler is the entering of the water into the jacket B', the rise of same through the openings b and c to section C, and the progress through the intermediate sections C' C' to the head-section C², whence 25 it proceeds by the flow-pipes L L.

What I claim is as follows—

1. In a hot-water boiler or furnace, water-sections in the form of hollow disks or chambers set horizontally, tapering from their center outward, having flues for the passage of 30 products of combustion, apertured hub portions forming the point of contact between these sections, and central diaphragms, the whole

adapted to secure an inclined centrifugal and centripetal passage of the water upward. 35

2. In a hot-water boiler or furnace, the combination, with the fire-chamber and a water-jacket surrounding same and communicating with the supply or return pipes, of water-sections in the form of hollow disks or 40 chambers in communication with said water-jacket and having flues for the passage of products of combustion, central apertured hub portions of greater depth than the outer edges or peripheries of such disks or chambers and forming the point of contact between each section and securing tapering sides for same, one or more of such sections having a central diaphragm adapted to compel the passage of the water radially from the center of 45 such section or sections to its or their sides or peripheries, flow-pipes leading from the uppermost of such sections, a suitable shell or casing encircling such sections, a stay passing centrally through the uppermost sections 50 and having one end secured within the lowermost section and the other end to the uppermost section, and means for securing said lowermost section to the fire-chamber section, as set forth. 55

Montreal, the 25th day of August, 1890.

DAVID LANCASTER DWINNELL.
